GAS MAIN STOPPER

Willis W. Gardner, Meriden, Conn.

Application June 18, 1935, Serial No. 27,183

4 Claims. (Cl. 138—94)

This invention relates to improvements in gas-main stoppers.

One object of this invention is to provide an improved gas-main stopper adapted to be quickly inserted in and removed from a gas-main.

Another object of this invention is to provide an improved gas-main stopper, so constructed as to be reliable and efficient in operation.

Another object of this invention is to provide an improved gas-main stopper formed of simple elements readily manufactured and readily assembled to produce a durable and efficient construction at minimum cost.

With the above and other objects in view, this invention includes all improvements over the prior art which are disclosed in this application.

In the accompanying drawings, in which certain ways of carrying out the invention are shown for illustrative purposes:

20 Fig. 1 is a front elevation of a gas-main stopper constructed in accordance with this invention, with the stopper-member indicated in dotted lines in the protector-case;

Fig. 2 is a right-side elevation, partly in section, of Fig. 1, with the diaphragm construction drawn upward within the tube;

Fig. 3 is a front elevation of the lower portion of the gas-main stopper, with the protector-case removed and the diaphragm construction shown in expanded operative relation in a gas-main;

Fig. 4 is a vertical, central, sectional view through the gas-main stopper, with the protector-case omitted and with the parts shown in the positions indicated in Fig. 1;

35 Fig. 5 is a transverse sectional view on line 5—5 of Fig. 1;

Fig. 6 is a transverse sectional view on line 6—6 of Fig. 3;

Fig. 7 is a transverse sectional view on line 7—7 of Fig. 4;

Fig. 8 is a perspective view of the piston-body;

Fig. 9 is a perspective view of the spring-connecting block; and

Fig. 10 is a bottom plan view of the spring-connecting block.

In the description and claims, the various parts are identified by specific names for convenience, but they are intended to be as generic in their application as the prior art will permit.

50 The tube 20 is screw-threaded at 21 at its lower end, for screw-threaded connection in a correspondingly-threaded hole in a gas-main 22 (Fig. 3). A cap 23 is threadedly secured to the upper 55 end of the tube 20, and preferably is also sweated

to firmly secure the cap in position. A vent-hole 34 extends through the parts 20 and 23.

Slidably fitting in the cylindrical opening 25 of the tube 20 is piston means including a piston 26 having screw-threadedly or otherwise connected thereto a hollow or tubular piston-rod 27.

Lubricant-passages 28 and 29 lead angularly outward from the central opening 30 in the piston 26 to the outer cylindrical surface 31 of the piston adjacent the inner cylindrical surface 25 of the tube 20. The lower inner end of the tube 20 is provided with an annular chamfered downwardly-flared surface 32.

The piston 26 is provided with two bosses 33 and 34, spaced apart to provide a central slot 15 35. Extending across and secured in holes 36 in the bosses are pins 37 and 38, which serve as pivots for the upper ends of the bowed springs 39 and 40. The lower ends of the bowed springs 39 and 40 are pivoted on pins 41 and 42 which are 20 respectively secured in pairs of spaced-apart ears 43 and 44 of a spring-connecting block 45. A cylindrical rod 46 is secured in a corresponding opening in the upper end of the block 45 by means of a drive fit and/or a pin-connection 47.

25 The tube 48 is provided with a vent-opening 48^a and has a sliding fit on the rod 46, and is firmly secured in the piston 26 in any suitable way as, for example, by means of a drive fit in a corresponding opening 49 in the piston. A loop of 30 felt 50, which may, if desired, be spliced together in any suitable way as at 51, forms a continuous loop extending all along the outer surfaces or sides of both springs 39 and 40 and along the bottom of the member 45, and across through the slot 35 in the piston 26, and has a hole so it can 35 be slid down over the tube 48. The springs 39 and 40 and the felt loop or ring 50 are covered by a diaphragm 52 formed of leather or other suitable material. The leather of the diaphragm 40 may be stitched along the lines 53 to enclose the felt and springs, as shown in Fig. 6. The upper 45 end 54 of the diaphragm 52 is firmly secured around the curved grooves 56 in the bosses 33 and 34, to make the diaphragm 52 gas-tight against the passage of gas from one side to the other of the diaphragm when in place in a gas-main. The 50 springs 29 and 40 and diaphragm 52 form the main parts of what may be called plug means.

55 The upper end of the hollow or tubular piston-rod 27 extends out through a cylindrical opening 57 in the cap 23, and has its upper end screw-threadedly connected, and preferably also sweated, in a corresponding screw-threaded 55

opening in the handle 58. The center-body of the handle 58 is provided with a screw-threaded opening 59 in which screw-threadedly fits a lubricant-feeding screw 60. The hollow piston-rod 27 is preferably filled with lubricant, such as grease, and by turning down the screw 60, the grease can be compressed and forced out through the openings 28 and 29, and around the annular groove 61 of the piston to thus lubricate the juxtaposed surfaces of the piston and cylinder, and also, during reciprocation of the piston, to carry lubricant to the chamfered annular surface 32.

In connecting the piston-rod and related parts together, care is taken to have the handle 58 extend in parallelism with the central plane extending through the members 39, 40, 46 and 48, so that when the stopper is to be applied to a gas-main, the position of the handle 58 will act 20 as a guide to the proper locating of the diaphragm across the gas-main.

For the purpose of protecting the plug means and leaving the bowed springs 39 and 40 in substantially-unstressed condition, a hollow protector-case 62 is used which may, if desired, be mainly formed of sheet-metal and have a screw-threaded ring 63 at its upper end adapted to screw on the screw-thread of the tube 20.

In order to apply the protector-case in position, the handle 58 is first pulled upwardly to draw the entire diaphragm construction up within the tube to the position shown in Fig. 2, whereupon the protector-case 62 is screwed in place on the threads 21 on the lower end of the tube 20, after which the handle 58 is pressed down to force the diaphragm construction including the bowed springs 39 and 40, to the position shown in Figs. 1 and 4, in which position the bowed springs are substantially unstressed and yet are completely protected against injury of any kind for normal transportation and storing of the device.

When the device is to be applied in use, the handle 58 is pulled upwardly to withdraw the diaphragm construction within the tube 20 in the position shown in Fig. 2, whereupon the protector-case 62 is unscrewed and removed. The screw-threaded end 21 of the tube 20 is then screwed into the corresponding screw-threaded opening in a gas-main 22 (Fig. 3), whereupon the handle 58 is arranged crosswise of the gas-main 22 to insure the proper positioning of the diaphragm construction, whereupon the handle 58 is pushed downwardly until the lower end of the diaphragm construction engages against the inside bottom surface 64 of the gas-main. As the handle is pushed still further down, the telescoping parts 46 and 48 slide together and the bowed springs are forced to bow outwardly and thrust the felt and its leather diaphragm into firm engagement with the cylindrical inner surface of the gas-main 22. In order to limit the movement of the handle downward to just the proper distance, a limit-ring or collar 65 is firmly secured in proper position to the piston 26 by means of a set-screw 66. Thus, when the limit-ring 65 engages against the top surface of the cap 23, the operator knows that the diaphragm is in properly located and expanded position. The piston is then locked in its proper position by means of the thumb-screw 67 which is screw-threadedly carried by the cap 23.

When the operations which are to be performed upon the gas-main are completed, the

thumb-screw 67 is loosened and the handle 58 is pulled upwardly, whereupon as the leather surface of the diaphragm covering the felt 50 engages against the annular chamfered surface 32 and the lubricant which will be thereon, the bowed springs 39 and 40 are sprung toward one another so as to permit the collapsed diaphragm construction to be completely drawn up in the tube 20, to the position shown in Fig. 2. When the diaphragm construction is in this completely withdrawn and protected position, the tube 20 is then unscrewed from the gas-main 22, whereupon the protector-case 62 is screwed in place on the threaded end 21 of the tube 20, and the handle is then again pushed down to bring the bowed springs 39 and 40 into their unstressed position shown in Figs. 1 and 4.

The invention may be carried out in other specific ways than those herein set forth without departing from the spirit and essential characteristics of the invention, and the present embodiments are therefore to be considered in all respects as illustrative and not restrictive, and all changes coming within the meaning and equivalency range of the appended claims are intended to be embraced therein.

I claim:

1. A gas-main stopper including: a tube adapted to have its lower end connected in an opening in a gas-main with the axis of said tube extending transversely of the axis of the gas-main; piston means including a tubular piston-rod and a piston, said piston being slidable in said tube and having a lubricant-passage leading to a location adjacent the inner surface of said tube; plug means including a pair of springs having their upper ends pivotally connected to said piston means and their lower ends pivotally connected together, said springs when unstressed being oppositely-outwardly bowed a distance substantially greater than the internal diameter of said tube; said tubular piston-rod being connected to said piston with the tubular passage of the piston-rod communicating with said lubricant-passage, and said tubular piston-rod extending out through the upper end of said tube.

2. In a gas-main stopper including a tube adapted to have its lower end connected in an opening in a gas-main with the axis of said tube extending transversely of the axis of the gas-main, and piston means slidable in said tube, and plug means including a pair of springs having their upper ends pivotally connected to said piston means and their lower ends pivotally connected together, and said springs when unstressed being oppositely-outwardly bowed a distance substantially greater than the internal diameter of said tube, and said piston means extending out through the upper end of said tube: means for protecting said plug means when not in operative position, comprising a protector-case having a maximum internal diameter substantially greater than the internal diameter of said tube and adapted to be detachably attached at the lower end of said tube and house said plug means with said springs in approximately unstressed condition.

3. In a gas-main stopper including a tube having its lower end screw-threaded for connection in a screw-threaded opening in a gas main with the axis of said tube extending transversely of the axis of the gas-main, and piston means slid able in said tube, and plug means including a pair of springs having their upper ends pivotally connected to said piston means and their lower

5 ends pivotally connected together, and said springs when unstressed being oppositely-outwardly bowed a distance substantially greater than the internal diameter of said tube, and said piston means extending out through the upper end of said tube: means for protecting said plug means when not in operative position, comprising a protector-case having a maximum internal diameter substantially greater than the internal diameter of said tube and adapted to be screw-threadedly detachably attached to said screw-threaded lower end of said tube and house said plug means with said springs in approximately unstressed condition.

10 4. A gas-main stopper including: a tube adapted to have its lower end connected in an opening

15 in a gas-main with the axis of said tube extending transversely of the axis of the gas-main; piston means slideable in said tube and having lubricant passage means adapted to deposit lubricant on the inner surface of said tube: plug means including a pair of springs having their upper ends pivotally connected to said piston means and their lower ends pivotally connected together, said springs when unstressed being oppositely-outwardly bowed a distance substantially greater than the internal diameter of said tube; said piston means being adapted to extend out through the upper end of said tube and having a tubular passage communicating with said lubricant-passage means.
